CLAIM

The ornamental design for a card slot bezel, as shown and described.

DESCRIPTION

FIG. 1 is a top, front, right side perspective view showing our new design for a card slot bezel.

FIG. 2 is a top, front, left side perspective view thereof.

FIG. 3 is a front view thereof.

FIG. 4 is a left side view thereof.

FIG. 5 is a right side view thereof.

FIG. 6 is a top view thereof; and,

FIG. 7 is a bottom thereof.

The broken lines adjacent the shaded areas represent the boundaries of the claimed design, while the other broken lines depict environmental subject matter only, and form no part of the claimed design. Also, the rear view forms no part of the claimed design.
